UNITED STATES PATENT OFFICE.

JAMES LEON WILLIAMS, OF NEW YORK, N. Y., ASSIGNOR TO THE DENTISTS' SUPPLY COMPANY, A CORPORATION OF NEW YORK.

ARTIFICIAL TOOTH.

Application filed January 29, 1920. Serial No. 354,978.

To all whom it may concern:

Be it known that I, JAMES LEON WILLIAMS, a citizen of the United States, and resident of New York city, county of New York, and State of New York, have invented an Improvement in Artificial Teeth, of which the following is a specification.

My invention has for its object an improved means for securing the frontal teeth in position upon the rubber vulcanite plate, dispensing with the employment of the usual pins attached to the back or lingual side of the tooth and substituting therefor an entirely different attaching means embodying in some respects the advantages of the mode of securing crowns in place upon the roots of natural teeth through anchoring pins.

My present invention has a further object comprehending the embedding of the porcelain tooth at its upper end and lingual side in the vulcanite denture plate and anchoring it in such relation by an angularly shaped anchor, one arm of which is of irregular cross section and fits down into a hole opening through the crown of the tooth and cemented therein, and the other arm extending rearwardly through a notch in the tooth to the lingual side of the tooth in which it is cemented and its rear portion embedded in the vulcanite material forming the plate, thereby not only anchoring the tooth in a vertical direction, but also laterally in the lingual direction, so that in rough biting there will be a minimum danger from possible detachment of the tooth from the plate.

My invention also has for an object the provision, in a combined frontal tooth and plate connected by means of an anchor, of capacity such that the anchor may assume different angular positions in respect to the tooth to adapt itself to various changes in the shape of the arch or roof structure of the plate, with any given positioning of the tooth; and also, with any given plate structure, provision is made for adjusting the tooth relative to the anchor in a buccal-lingual direction whereby the tooth may be given different angular positions relative to the plate. With this capacity for relative adjustment of the anchor in respect to the tooth, both the positioning of the anchor and the tooth may be variously made

in respect to the plate to suit requirements of various mouths.

My invention, also consists of improvements hereinafter described whereby the above objects and results are attained, said improvements comprising certain organization and combination of parts which are fully described hereinafter and more particularly defined in the claims.

Referring to the drawing: Fig. 1 is a vertical sectional view taken bucco-lingually through a plate and one of the frontal teeth, showing the means of union; Fig. 2 is a perspective view of my improved tooth; Fig. 3 is an elevation of the tooth shown in Fig. 2, from the lingual side; Fig. 4 is an enlarged view of a portion of the tooth shown in Fig. 3, but illustrating the attachment of the anchoring pin; Fig. 5 is a perspective view of the general form of my improved anchoring pin; Fig. 6 is a plan view of the tooth with the anchor in place; Fig. 7 is a diagrammatic view corresponding to Fig. 1, but showing the adjustable capacity of the tooth with respect to the anchor and plate; and Fig. 8 is a similar diagrammatic view illustrating the capacity for the adjustment of the anchor relative to the tooth to correspond to variations in the shape of the plate.

2 is the tooth and 3 the vulcanite plate to which the tooth is attached and anchored in position by anchor 4. Referring to the general construction of the porcelain tooth 2, it has its upper part formed with the ridge 14 and the downwardly curved crown surface 5 terminating at the lingual face in the vertical or lingual wall 8. The surface 5 of the tooth is deeply recessed to provide a hole 6 which is preferably somewhat tapering with the larger diameter near the top in a buccal-lingual direction, and in horizontal cross section this hole is preferably more or less elliptical and greatly wider mesio-distally than in the direction between the buccal and lingual surfaces. The hole thus provided is opened to the lingual side 8 of the tooth by a notch 7, preferably dovetailed or undercut, as shown, being widest at the bottom.

The tooth above described, is fitted with the angular anchor 4, having the vertical portion 10 which extends down into the hole 6 therein and is cemented in position,

as at 9 (Fig. 1). The upper or shank portion 13 of the anchor 4 is extended rearwardly and with a slight upward curvature, the extreme rear end being preferably 5 looped shape as at 12, said rearwardly extending shank being wholly embedded in the vulcanite plate 3, as shown, the vulcanite material locking the anchor in place by extending through the opening 12 therein and 10 in front of the outer shoulders of the looped end. The general angle between the vertical portion 10 and the shank portion 13 with its rear extension thereof is preferably greater than 90°. The anchor is preferably 15 made flat and extended rearward and curved upward to properly fit the vulcanite plate where it curves upward to fit the roof of the mouth. I prefer to provide the lower end 10 of the anchor with transverse grooves 20 11 which insure recesses or abrupt shoulders to take a stronger hold in the vulcanite or other cement 9 employed to fill the hole 6 in the tooth. This anchor 4 has its rearwardly extending shank positioned in the 25 notch 7 of the tooth and cemented therein, as showing at 9^a, in Fig. 4, wherein the side edges of the shank are preferably beveled at 4^a so as to make the shank wider at its under surface than at its upper surface and 30 thus cause it to be locked in position by the cement. It will also be seen that the side walls 7^a of the notch 7 are, in effect, beveled or undercut, so that the cement 9^a is firmly locked in position and thus firmly 35 holds the anchor part 4^a of the anchor shank rigidly in position upon the tooth.

From the foregoing construction, it will be seen that the tooth is held between buccal and lingual flanges or extensions 3^a and 3^b, 40 respectively, of the plate 3; and its upper surface is so fitted to the plate that a powerful down thrust may be had without undue strain. It will be further seen, that the tooth is strongly anchored to the plate by 45 the metal anchor 4 in such a manner that it is held vertically to the plate and, moreover, is held from breaking away from the plate when subjected to strong outward thrust upon the incisor end from the lingual to the 50 buccal side during rough biting efforts. It will be noted that the ridge 14 of the tooth snugly fits in the body of the plate, in a socket 14^a, as it were, (Fig. 1), and thereby prevents any slipping or displacement outwardly at the upper part of the tooth; and therefore, the anchor is especially useful in 55 holding the incisor end of the tooth from moving outward and separating from the the plate. Aside from the fact that the 60 anchor 4 is rigidly secured to the tooth and hence holds it in a vertical direction, it acts much like a hook to hold the tooth body to the lingual lap or shoulder 3^b. From Fig. 65 1, it will be observed that the vulcanite material of the plate 3 extends down into the

opening of the hole 6 and also into the notch 7 and this further holds the tooth in proper position to resist all displacement during mastication; and the flat form of the shank 10 of the anchor fitting the wide hole 6 of 70 the tooth strengthens the structure against loosening the tooth by torsional strain.

It will be observed that the rear arm or shank of the angular anchor 4 is capable of vertical adjustment within the slot 7 75 of the tooth, and, similarly, the vertical arm 10 of the anchor is capable of swinging about the bottom of the hole to assume different angular positions within the tapered aperture 6 of the tooth 2, whereby the rear end of the anchor may assume various elevations relatively to the tooth when associating it and the tooth with the vulcanite plate 3. Also assuming that the anchor 4 is to have a definite position in the vulcanite plate 3, then it will also be evident that the tooth 2 may be rocked upon the bottom of the arm 10 of the anchor to position it buccal-lingually with respect to the plate and with the effect that the incisor end is caused to be positioned in a more outward or buccal direction or in a more inward or lingual direction, as may be required for proper occlusal cooperation with the lower teeth. In the making of dentures, the shape of the plate is largely governed by the shape of the upper jaw of the patient, and, similarly, the position of the tooth must be governed for proper co-action with the lower teeth, and, therefore, there must be a capacity for relative adjustment which will permit the angular anchor to be employed and at the same time be both properly positioned in the plate and thoroughly secured in the hole 6 and notch 7 90 of the tooth. This capacity is secured by making the hole 6 wider in a buccal-lingual direction (and preferably tapering) than the arm 10 of the anchor and, at the same time, to provide greater depth in the notch 100 7 than the vertical thickness of the rear arm or shank of the anchor, whereby the tooth may be adjusted relatively to the anchor without the said shank coming above the upper portion of the notch. Furthermore, the space in the notch in the hole of the tooth must be sufficiently large that the vulcanite or cement may work its way down thereinto and securely hold the anchor in position within the tooth. This capacity will be better understood by reference to the two diagrammatic Figs. 7 and 8 which, while corresponding to Fig. 1, indicate the six possible positions of extreme 115 adjustments or relative positioning of the 120 parts.

Referring to Fig. 7, the solid lines correspond in general to the construction of Fig. 1, but assuming the plate to be that which is required, it will be possible with 130

my invention to provide adjustments of the tooth 2 relatively to the anchor and plate so that the incisor end of the tooth may take the position 2^a inward or in a lingual 5 direction, or in an outward or buccal direction as indicated at 2^b. This enables the teeth to be properly positioned to co-act with the lower teeth. The adjustment mentioned would be made at the time the vul- 10 canite was applied to the teeth in making the denture.

Referring to Fig. 8 of the drawing, the solid lines correspond to those of Fig. 7 and, therefore to Fig. 1, but the dotted 15 lines in respect to the plate and the anchor indicate a possible adjustment of the latter to suit the different shapes of the plate which may be necessary to suit the roof of the mouth of the patient, and assuming, of course, that there was no necessity for any 20 adjustment in respect to the position of the tooth. In this construction, it will be seen that where the roof of the plate is required to be low, as at 3^c, the rear end of the anchor must assume a lower position to remain embedded in the vulcanite and, therefore, the position of the anchor in the hole and slot of the tooth is changed, as is indicated by the dotted lines 4^a. Similarly, 25 if the roof of the patient is high, the plate must be raised in its curvature to correspond to 3^a and in this event, the rear end of the anchor 4 must be raised to maintain its embedment within the vulcanite, as indicated at 4^b, and here again, the anchor as a whole will have taken on a new adjustment in respect to the tooth.

It will be further understood that the 30 adjustments of the teeth, as in Fig. 7, and the shaping of the plate and adjustments 40 of the anchor of Fig. 8 may be embodied in the same denture and this is made possible by the employment of my improvements.

In the modification shown in Fig. 6, the 45 notch 7 has its side walls 7^a at an angle to each other in a horizontal plane as well as in a vertical plane. This gives to the notch a dovetail shape in plan, and when 50 the shank part 13 of the anchor 4 is made tapering to fit the notch, as shown, and the parts locked by cement, a very strong connection is provided.

While I prefer to make the metal anchor 55 from stamped sheet metal such as nickel alloy, I do not restrict myself in this respect, as it may be made of any suitable metal or alloy and may be cast if so desired. It will be observed that in the structure herein set out, the metal anchor and the cement are wholly covered and protected against attacks by acids of the mouth and hence is a most desirable construction.

I have shown my invention as applied 60 to one of the front incisor teeth, but it is

to be understood that it equally applies to all of the frontal teeth, and in fact to any teeth where its use may be found advantageous.

It will now be apparent that I have devised a novel and useful construction which embodies the features of advantage enumerated as desirable, and while I have in the present instance shown and described the preferred embodiment thereof which 75 has been found in practice to give satisfactory and reliable results, it is to be understood that I do not restrict myself to the details, as the same are susceptible of modification in various particulars without departing from the spirit or scope of the invention.

Having now described my invention, what I claim as new and desire to secure by Letters Patent, is:—

1. An artificial tooth and an anchor therefor adapted for use in dentures wherein the tooth has its upper part provided with a deep hole of greater width transversely than in a lingual-buccal direction, and said hole at the lingual side terminating in a rearwardly directed deep notch extending to the rear wall of the tooth, and in which the anchor has a vertical part of greater width than thickness extending down into the hole of the tooth and cemented therein and also provided with a rearwardly and upwardly projecting shank extending through and cemented in the deep notch of the tooth, and wherein further the side walls of the notch of the tooth are undercut for firmly holding the cement in which the rearwardly extending part of the anchor shank is embedded.

2. An artificial tooth and an anchor therefor adapted for use in dentures wherein the tooth has its upper part provided with a deep hole of greater width transversely than in a lingual-buccal direction, and said hole at the lingual side terminating in a rearwardly directed deep notch extending to the rear wall of the tooth, and in which the anchor has a vertical part of greater width than thickness extending down into the hole of the tooth and cemented therein and also provided with a rearwardly and upwardly projecting shank extending through and cemented in the deep notch of the tooth, and wherein further the notch of the tooth is made tapering in a horizontal plane and the shank of the anchor extending through the notch is also tapering in width to increase the stability of the union between the tooth and shank of the anchor in a horizontal direction.

3. The invention according to claim 1, wherein the shank is also beveled on its side edges to give a greater width at the lower surface than at the upper surface, whereby the anchor shank is dove-tailed into the

cement and the cement is dove-tailed into the notched portion of the tooth.

4. A combined artificial tooth having a flat back for approximately one-third of its height, and anchor in association with the vulcanite of the denture plate, wherein the tooth has its upper part provided with a deep hole and deep rearward notch, and the vulcanite of the denture plate is fitted 10 over the top of the tooth and into the upper portions of the hole and notch and also downward along the flat back of the tooth for approximately one-third of the height thereof whereby the tooth is positively held 15 against turning about an upright axis, said anchor made of flat metal of an angular shape having one portion extending down into the hole of the tooth and cemented therein and having the other and upper or 20 shank portion thereof extending rearwardly and upward and embedded in the material of the denture and plate substantially midway of its upper and lower surfaces.

5. An anchor for attaching a tooth to a 25 denture plate consisting of an angular shaped bar of flat metal, one part of which extends vertically for direct insertion into the tooth said part being of greater width than thickness of irregular surface form, 30 and the other part also of greater width than thickness of irregular surface form, and upwardly and terminating in a looped portion for attachment to the denture plate.

6. The invention according to claim 5, 35 further characterized by having the sides of the rearwardly extending portion adjacent to the vertical part provided with oppositely beveled side edges.

7. An artificial tooth having a vertical 40 hole therein closed on all sides at its bottom and of greater width transversely than in a buccal-lingual direction, said hole also being tapered from its bottom outwardly and in a buccal-lingual direction and also 45 having a rearwardly extending deep notch of less width than the hole and arranged

between the hole and the lingual wall of the tooth, the depth of said notch being greatly more than the vertical thickness of the anchor with which it is to be employed 50 but of less depth than the hole.

8. An artificial tooth having a vertical hole therein closed on all sides and of a greater width transversely than in a buccal-lingual direction, said hole opening at the 55 top of the tooth and also having a rearwardly extending notch between the hole and the lingual wall of the tooth, said notch having its side walls made undercut.

9. An artificial tooth having a vertical 60 hole therein of greater width in a direction mesio-distally than in a buccal-lingual direction, said hole also being tapered from its bottom outwardly and in a buccal-lingual 65 direction and also having a rearwardly extending deep notch of less width than the hole and arranged between the hole and the lingual wall of the tooth, the depth of said notch being greatly more than the vertical thickness of the anchor with which it is to be employed, combined with an angular anchor of metal having a vertical part of greater width than thickness fitting in the vertical hole of the tooth and adapted to be adjusted therein at various angles 70 in a lingual-buccal plane and having a rearwardly extending arm adjustable vertically in the notch of the tooth and of a vertical thickness greatly less than the vertical depth 75 of the notch, and a vulcanite plate fitting the back and top of the tooth and extending down into the hole and notch thereof and surrounding the anchor on all sides, the anchor being adjustable in the hole and notch 80 of the tooth when shaping the plate to permit its rear arm to be wholly embedded within the vulcanite of the roof portion of the plate.

In testimony of which invention, I hereunto set my hand.

JAMES LEON WILLIAMS.
